UNITED STATES PATENT OFFICE.

JOHN R. MARDICK, OF NEW YORK, N. Y., ASSIGNOR TO ELECTRO METALLURGICAL COMPANY, OF NIAGARA FALLS, NEW YORK, A CORPORATION OF WEST VIRGINIA.

EXPLOSIVE.

1,335,788.

Specification of Letters Patent.

Patented Apr. 6, 1920.

No Drawing.

Application filed December 15, 1917. Serial No. 207,389.

To all whom it may concern:

Be it known that I, JOHN R. MARDICK, a citizen of the United States, residing at New York, in the county of New York and State of New York, have invented certain new and useful Improvements in Explosives, of which the following is a specification.

This invention relates to certain novel explosive compositions suitable for blasting and other purposes, and containing as essential components one or more normally solid nitro-aromatic bodies having at least three nitro-groups, of which tri-nitrotoluene (T. N. T.) and picric acid are types, associated with an oxidizing agent or agents, and with ferrosilicon. The ferrosilicon is present in substantial proportions, preferably between the limits of five and fifteen per cent. of the total weight; and the nitro-aromatic body is present in sufficient proportion, and in conjunction if necessary with certain low melting-point components, preferably liquid or easily liquefiable dinitro bodies, to impart to the composition as a whole the desired plastic or cohesive character; for this purpose the nitro body should be in excess by weight of the ferrosilicon. The oxidizing agents used are preferably the nitrates, chlorates and perchlorates of the alkali metals (including ammonium), or mixtures of these salts at times in conjunction with nitrates of heavy metals such as lead or barium. Other components usually present in the mixture comprise any suitable combustible material typified by wood flour or meal; a small proportion of calcium carbonate or other suitable substance acting as an anti-acid; and if required a waterproofing or coating substance, this latter being used more particularly in case hygroscopic salts such as ammonium nitrate are present in the mixture.

A general formula for an explosive composition embodying my invention is as follows:

	By weight.
Nitro aromatic compound or compounds	15-30%
Ferrosilicon	5-15%
Oxidizer	50-75%
Combustible	1-5%
Anti-acid	0-1%

Following are certain illustrative formulae:

Blasting explosives.

	Parts by weight.	55
(1) T. N. T. or picric acid	20	
Ferrosilicon 82%	12	
Ammonium nitrate	40	60
Sodium nitrate	21.5	
Dinitrotoluol	3	
Wood flour	3	
Calcium carbonate	0.5	
(2) T. N. T. or picric acid	25	65
Ferrosilicon 82%	7	
Potassium perchlorate	50	
Sodium nitrate	12.5	
Wood flour	5	
Calcium carbonate	0.5	70
(3) T. N. T. or picric acid	20	
Ferrosilicon 82%	12	
Ammonium perchlorate	35	
Sodium nitrate	26.5	
Dinitrotoluol	3	75
Wood flour	3	
Calcium carbonate	0.5	

Torpedo charge.

(4) T. N. T. or picric acid	20	80
Ferrosilicon 82%	10	
Lead nitrate	40	
Ammonium nitrate	15	
Sodium nitrate	7.5	
Dinitrotoluol	3	85
Wood flour	4	
Calcium carbonate	0.5	

Formulae 1-3 are commercial (blasting) explosives of the plastic or cohesive type, capable of being tamped into place and comparing favorably in their effect with commercial grades of dynamite. Formula number 4 is a torpedo explosive which possesses exceptional striking power by reason of its relatively large content of lead nitrate. 95

Each of the essential components of the explosive performs a function in the mixture, and the proportions of the components will be varied in practice as may be necessary to the proper performance of this function, having in view the specific purpose for which the explosive is intended. 100

The nitro-aromatic bodies are normally solid but readily fusible, and are therefore

easily compounded with the other ingredients, yielding transportable granular plastic or cohesive compositions which are readily tamped into conformity to the bore. Instead of T. N. T. or picric acid I may use other nitro-aromatic bodies having similar desirable qualities, as for example tri- and tetra-nitro-naphthalene, and the tri-nitro cresols. Nitro-aromatic bodies having less than three nitro-groups are not equivalent to these.

The oxidizer is in sufficient proportion to convert any carbon monoxide into carbon dioxide and serves in general to oxidize all poisonous or objectionable gases or compounds, rendering the products of explosion innocuous. In the case of commercial explosives it is also used in sufficient excess to effect oxidation of the paraffined paper wrapper usually employed. The wood flour or other combustible will unite with any otherwise unconsumed excess of the oxidizing component. The use of the anti-acid body is precautionary, guarding against development from any cause of an acid condition in the mixture.

In case a hygroscopic salt such as ammonium nitrate is used I prefer to introduce into the mixture small proportions, say four per cent. or less, of a liquid capable of coating the salt and thereby protecting it from atmospheric moisture. For this purpose I may use vaseline, oils, etc.; but I prefer liquid nitro bodies, such for example as the commercial liquid nitro xylenes, o-dinitro benzene, dinitro toluene or the like. These liquid nitro bodies act as deadening agents, and therefore should not be used in excessive proportions.

Ferrosilicon as a reducing agent presents marked advantages over metallic reducers such as aluminum, magnesium, or even silicon itself. Among such advantages are to be mentioned the following:

(1) Improved stability of the mixture and freedom from tendency to deteriorate through slow oxidation.

(2) Decreased sensitiveness of the mixture. The mixtures formulated above require a relatively heavy detonator, preferably No. 7.

(3) Ferrosilicon is readily pulverized to 100 mesh or finer, yielding a relatively heavy powder. This results in a reduced bulk of the explosive mixture for a given weight and power.

(4) The iron component of the ferrosilicon is also oxidized, yielding with the silicon a relatively heavy oxid mixture, as compared for example with aluminum, magnesium, or silicon alone. In this connection it will be understood that the blow exerted by the solid particles is a material factor in the *brisance* or shattering effect of the explosive. This effect is greatly enhanced by

the use of lead nitrate additions, as in formula No. 4, by reason of the heavy oxidation products formed.

The 82% ferrosilicon mentioned in the specific formula may be replaced by higher or lower grades, particularly such as are readily pulverized to 100 mesh or finer. Ferrosilicon containing less than 50 to 60 per cent. of silicon is undesirable.

The higher grades of ferrosilicon merge into the commercial grades of silicon; and while I prefer to use ferrosilicon by reason of the advantages before set forth, I regard it as within my invention to substitute silicon therefor; and both silicon and ferrosilicon are intended to be covered by the expression "silicon-containing substance" employed in certain of the claims.

I claim:

1. A plastic explosive containing as essential components a normally solid fusible nitro-aromatic body having at least three nitro-groups, an oxidizer, a plasticizing ingredient, and a silicon-containing substance, said components proportioned to confer plasticity on the composition.

2. A plastic explosive containing as essential components a normally solid fusible nitro-aromatic body having at least three nitro-groups, an oxidizer, a plasticizing nitro-body, and a silicon-containing substance, said components proportioned to confer plasticity on the composition.

3. A plastic explosive containing as essential components a normally solid fusible nitro-aromatic body having at least three nitro-groups, an oxidizer, a plasticizing ingredient, and ferro-silicon, said components proportioned to confer plasticity on the composition.

4. A plastic explosive containing as essential components a normally solid fusible nitro-aromatic body having at least three nitro-groups, an oxidizer, a plasticizing nitro-body, and ferro-silicon, said components proportioned to confer plasticity on the composition.

5. A plastic explosive containing as essential components a normally solid fusible nitro-aromatic body having at least three nitro-groups, 15-30%; an oxidizer 50-75%; a silicon-containing substance 5-15%; and a relatively small proportion of a plasticizing ingredient; said components proportioned to confer plasticity on the composition.

6. A plastic explosive containing as essential components a normally solid fusible nitro-aromatic body having at least three nitro-groups, 15-30%; an oxidizer 50-75%; a silicon-containing substance 5-15%; and a relatively small proportion of a plasticizing nitro-body; said components proportioned to confer plasticity on the composition.

7. A plastic explosive containing as es-

sential components a normally solid fusible nitro-aromatic body having at least three nitro-groups, 15-30%; an oxidizer 50-75%; ferro-silicon 5-15%; and a relatively small proportion of a plasticizing ingredient; said components proportioned to confer plasticity on the composition.

5 8. A plastic explosive containing as essential components a normally solid fusible

nitro-aromatic body having at least three 10 nitro-groups, 15-30%; an oxidizer 50-75%, ferro-silicon 5-15%; and a relatively small proportion of a plasticizing nitro-body; said components proportioned to confer plasticity on the composition.

15 In testimony whereof I affix my signature.

JOHN R. MARDICK.
